UNITED STATES PATENT OFFICE

2,027,630

ROADWAY MACHINE

Martin D. Bowen, Savanna, Ill.

Application April 25, 1934, Serial No. 722,354

4 Claims. (Cl. 184—3)

This invention relates to railway maintenance-of-way equipment and has for its principal object to provide simple and economical apparatus for oiling the fish joints or rail joints that will travel along the rails and deliver a blast of oil-bearing air, and that can be readily rolled laterally off the track to let a train pass, and back again afterwards, without being disorganized.

Further objects and advantages of the invention will become apparent as the description is read in connection with the accompanying drawings, in which

Fig. 1 is a perspective view showing one embodiment of the invention on a section of railway track;

Fig. 2 is a longitudinal vertical section through the air and oil tank and one end of the carriage;

Fig. 3 is a transverse section taken on the line 3—3 of Fig. 2, and

Fig. 4 is a somewhat diagrammatic end view showing the device in solid lines on the track and in dotted lines rolled to one side thereof.

But this drawing and the corresponding description are used for the purpose of disclosure only, and are not intended to impose limitations on the claims.

The main frame of the carriage includes three tubular hoops 10, 11 and 12, connected by three tubular side pieces 13, 14 and 15, and two angular side pieces 16 and 17, all welded to the peripheries of the three hoops.

The side pieces 16 and 17 take the place of sleepers for the carriage and are equipped with aligned flanged wheels 18, journaled in boxes 19, welded to the sleepers.

A socket piece 20 welded to the top of the angle pieces 16 and 17, receives one end of a guide bar 21, the other end of which is equipped with a roller 22 for engagement with the rail 23 opposite to that on which the wheels 18 run.

Each of the end hoops 10 and 12, is welded to the outer ends of tubular spokes 24, the inner ends of which are welded into hub structures comprising perforated plates 25 and tubes 26, all welded together. After the welding the tubes 26 are bored out and finished, or bushed, to receive trunnions 27 and 28, welded to channels 29, which, together with side angles 30, form hangers for a rectangular apparatus bed composed of side channels 31 and end channels 32, all welded together to form one integral piece.

Assembled on the apparatus bed 31, from left to right, in Fig. 1, is a gasoline engine 33, connected by a V-belt drive 34 with an air com-

pressor 35, in turn connected by a coil tube 36 to a tank 37.

By arranging the apparatus in this wise, the shafts 38 and 39 of the engine and the air compressor are placed crosswise to the apparatus bed 5 and both the starting crank 40 and the belt drive 34 are made easily accessible.

The tubing 36 is connected to a pipe 41, (Fig. 2) extending through and welded to the heads 42 and 43 of the tank, and provided with perforations 44 distributed substantially throughout that portion of its length exposed to the interior of the tank.

A full charge of oil should have a level in the neighborhood of that indicated at 45, hence the 15 air from the compressor will be delivered well below the surface of the oil and so directed as to cause circulation adapted to keep all solid matter in suspension and prevent any obstructing accumulation in the bottom of the tank. 20

The compressor shown has air cooling fins 46, but no other cooling is used, to the end that the entering compressed air may be hot enough to warm up the oil and make it highly fluid.

A hose nipple 47 (Fig. 2) extends through the 25 hollow trunnion 28 and is connected with a suitable length of hose 48, fitted with a nozzle 49 having flattened discharge 50 adapted to deliver a mixture of compressed air and entrained oil into the cracks between the fish plates or 30 angle bars 51 and the rails 23.

Oil is taken from adjacent to the bottom of the tank through a nipple 52, welded in the head 43, and connected by an elbow 53 with an upright pipe 54, leading to a T 55 into which the 35 hose nipple 47 is screwed.

Air is taken from the upper side of the tank through a nipple 56 welded to the tank and connected by piping 57 with an atomizer nozzle 58 comprising a tube welded to a bushing 59 threaded 40 into the T 55.

The atomizer nozzle used in this particular embodiment is $\frac{1}{2}'' \times 6''$, the bushing 59 is a standard $\frac{3}{4}'' \times 1\frac{1}{4}''$, and the T 55 is a standard $1\frac{1}{4}'' \times 1\frac{1}{4}'' \times \frac{3}{4}''$. These dimensions will 45 sufficiently indicate the sizes required for success.

The flow of air and oil is controlled primarily, and their relative proportions regulated by gate valves 60 and 61, respectively. The delivery through the nozzle 49 is controlled by a quick 50 operating valve 62 of the Lunkenheimer grip lever type, connected between the nozzle 49 and a hose nipple 63, which latter forms a handle to be enclosed in the operator's hand with the grip lever 64 of the valve 62. 55

The main frame of the carriage is 30" in diameter and 72" long, the engine illustrated is a 3" bore x 3 1/4" stroke, 4 cycle single cylinder L head, air cooled, gasoline motor having a speed range of approximately 1800 to 2600 R. P. M. and known to the trade as Briggs & Stratton Model Z.

The air compressor is a single cylinder 3 3/8" x 3 1/2", known to the trade as a Curtis No. 50. 5 The apparatus as a whole is comparatively light, and can be pushed along easily by one man, who also watches for coming trains and can quickly throw the machine from the solid to the dotted line position in Fig. 4, and back again. 10 15 Another man handles the nozzle and adjusts the air and oil.

The quick operating valve enables him to start and stop the flow by simple movement of his fingers in gripping and releasing the lever 64. In 20 starting, of course, he will hold the valve 62 open and adjust the valves 60 and 61 until the proportions of air and oil are right, after which the flow is entirely controlled by squeezing and releasing the grip lever.

25 One particular advantage of this equipment is that it permits the oil to be put behind the angle bars or fish plates directly at the surfaces to be lubricated. The flattened nozzle causes the stream to be delivered in a thin blade or sheet, best suited to enter the joint without waste.

The air pipe 41 is shown in Fig. 2 a considerable distance above the bottom of the tank and the nipple 52 is shown above it. This is merely for convenience in illustration. Actually the pipe 35 41 is only about half an inch from the bottom of the cylindrical tank, and the nipple 52 is alongside it about the same level.

30 The oil used for this purpose contains various foreign matter including solids, tars, waxes, etc., and when the apparatus is not in use there is a 40 tendency for this material to settle in and clog the pipe 41. To facilitate cleaning the right end

is fitted with a plug 65 and the left end with a union 66. When these are removed a rod or other cleaning device may be run through the entire length of the pipe.

I claim as my invention:—

5 1. A railway track oiler comprising a wheeled vehicle having a tank for oil and air, means to deliver compressed air to the tank below the surface of the oil, a mixer, valve controlled means connecting the mixer with the tank adjacent to the bottom, other valve controlled means connecting the mixer with the tank adjacent to the top, and a valved delivery nozzle connected to the mixer to receive mixed oil and air therefrom.

10 2. A railway track oiler comprising a wheeled vehicle having a tank for oil and air, means to deliver compressed air to the tank below the surface of the oil, a mixer, valve controlled means connecting the mixer with the tank adjacent to the bottom, other valve controlled means connecting the mixer with the tank adjacent to the top, a delivery nozzle, a hose connecting the mixer with the delivery nozzle, and a valve in the delivery nozzle for controlling the discharge of the mixed oil and air.

15 25 3. A railway track oiler comprising a wheeled vehicle having a tank for oil and air, means to deliver hot compressed air to the tank below the surface of the oil, a mixer, valve controlled means connecting the mixer with the tank adjacent to the bottom and other valve controlled means connecting the mixer with the tank adjacent to the top.

30 35 4. A railway track oiler comprising a carriage including a hollow frame adapted to roll laterally, an apparatus bed, means for mounting the bed on the carriage including a hollow trunnion, a tank for oil and air on the bed and tubular delivery means connected with the tank and extending through the trunnion.

40 MARTIN D. BOWEN.
